(57) **CLAIM**

The ornamental design for a hand-held vacuum cleaner, as shown and described.

DESCRIPTION

FIG. 1 is a front view of a hand-held vacuum cleaner showing my new design;

FIG. 2 is a rear view thereof;

FIG. 3 is a right side view thereof, the left side being a mirror image;

FIG. 4 is a top plan view thereof;

FIG. 5 is a bottom plan view thereof; and,

FIG. 6 is a left side perspective view thereof.

The areas outlined in broken lines in FIGS. 3, 4 and 6 form no part of the claimed design.
